UNITED STATES PATENT OFFICE.

THOMAS L. LAWTON, OF PHILADELPHIA, PENNSYLVANIA.

DESIGN FOR A CARPET.

Application filed April 26, 1923. Serial No. 5,968. Term of patent 3½ years.

To all whom it may concern:

Be it known that I, THOMAS L. LAWTON, a citizen of the United States, residing at Philadelphia, in the county of Philadelphia and State of Pennsylvania, have invented a new, original, and ornamental Design for a Carpet, of which the following is a specification, reference being had to the accompanying drawing, forming part thereof.

The figure is a plan view of a section of a carpet, showing my new design.

I claim:

The ornamental design for a carpet, as shown.

THOMAS L. LAWTON.
